(57) **CLAIM**

The ornamental design for a pillow, as shown and described.

DESCRIPTION

FIG. 1 is a perspective view of a pillow, showing my new design;

FIG. 2 is an end elevational view, the opposite end being identical thereto;

FIG. 3 is a side elevational view, the opposite side being identical thereto;

FIG. 4 is a top plan view thereof;

FIG. 5 is a bottom plan view thereof;

FIG. 6 is a perspective view of a pillow, showing a second embodiment of my new design;

FIG. 7 is an end elevational view, the opposite end being identical thereto;

FIG. 8 is a side elevational view, the opposite side being identical thereto;

FIG. 9 is a top plan view thereof;

FIG. 10 is a bottom plan view thereof;

FIG. 11 is a perspective view of a pillow, showing a third embodiment of my new design;

FIG. 12 is an end elevational view, the opposite end being identical thereto;

FIG. 13 is a side elevational view, the opposite side being identical thereto;

FIG. 14 is a top plan view thereof; and,

FIG. 15 is a bottom plan view thereof.
